UNITED STATES PATENT OFFICE

1,967,240

AUTOMATIC CONTROL FOR CRUSHING MACHINES

William W. Guest, Los Angeles, Calif., assignor to
Mary E. Guest, Los Angeles, Calif.

Application December 6, 1930, Serial No. 500,573

4 Claims. (Cl. 83—53)

My invention relates generally to rock crushing machines of the type disclosed in my co-pending application for U. S. Letters Patent filed May 26, 1930, Serial No. 455,793, and more particularly to an automatic control or switch actuating device, and the principal object of my present invention is, to provide relatively simple, practical and efficient means for actuating a switch in the electric connections that lead from a source of current supply to the electric motor that operates the crushing machine and which control or switch actuating means functions as a safety factor, in that it operates automatically in the event that a piece of uncrushable material or a foreign object such as a piece of metal enters the machine and passes between the jaws thereof.

In the operation of rock crushing machines, it sometimes happens that an uncrushable object or piece of material passes between the crushing jaws, with the result that said jaws, or other parts of the machine are distorted or broken and it is the purpose of my invention to provide a device that will act automatically in the event that the jaws encounter a piece of uncrushable material and which device cuts out the electric motor that drives the crushing machine, consequently preventing breakage in the machine and eliminating loss of time and cost of repairs and replacements.

Further objects of my invention are, to provide an automatic control device that is associated with the spring cushion that yieldingly resists the outward movement of the yielding jaw of the crushing machine and, further, to provide in the control device, an adjustment whereby the operation of said control device may be very accurately controlled and regulated.

With the foregoing and other objects in view, my invention consists in certain novel features of construction and arrangement of parts that will hereinafter be more fully described and claimed and illustrated in the accompanying drawing in which:

Fig. 1 is a vertical section taken through the center of a yielding jaw rock crushing machine and showing my improved automatic cutoff and control associated with the spring cushion thereof.

Fig. 2 is an enlarged vertical section taken through the center of the spring cushion and the automatic cutoff.

Fig. 3 is a perspective view of the outer end of an adjustable rod that forms a part of the automatic cutoff.

Referring by numerals to the accompanying drawing which illustrates a practical embodiment

of my invention, 10 designates the frame of a yielding jaw rock crushing machine, 11 the hopper thereof, 12 the swinging jaw that is operated by an eccentric 13 and 14 the yielding jaw.

The crusher is operated in the conventional manner by an electric motor (not shown).

Formed through the lower portion of frame 10, to the rear of the lower end of jaw 14, is an opening 15, through which passes the spring cushion that yieldingly opposes the outward swinging movement of the yielding jaw.

Supported in any suitable manner, preferably by bolts that project outwardly from the frame of the machine adjacent to the ends of the opening 15, is a spring beam 16, against which bear the outer ends of relatively stiff expansion springs 17, which constitute the resilient members of the spring cushion. These springs pass through opening 15 in frame 10 and their inner ends rest upon a thrust plate 18 that is pivotally connected to the lower rear portion of jaw 14.

Rods 19 extend from the thrust plate through the springs 17 and through the spring beam 16 and the threaded ends of the rods that project beyond the spring beam receive nuts 20.

Secured in any suitable manner to the center of thrust plate 18 and projecting outwardly therefrom is a fork 21, to which is pivotally connected the inner end of a distance rod 22, the outer end portion thereof being provided with a threaded axial bore 23.

Screw seated in said bore is the threaded inner portion of a rod 24 and the outer end portion of this rod is arranged for sliding movement in an aperture 25 that is formed through spring beam 16.

The lower half of the outer end portion of rod 24 is cut away so as to provide a relatively short flat underface 26 and formed in the outer end of said rod is a short slot 27 that is adapted to receive the point of a screw driver or like tool when said rod is adjusted in the distance rod 22 by screwing said rod 24 into or out of said distance rod.

A portion of the jaw immediately to the rear of the flat face 26 is cut away to form a flat underface 28 that is somewhat longer than face 26 and formed between said flat underfaces 26 and 28 is an inclined face 29.

Arranged in the lower portion of the spring beam 16 directly beneath the center of aperture 25 is a vertically disposed housing 30, within which is arranged for sliding movement, a plunger 31 and projecting upwardly from this plunger into the aperture 25 is a stem 32. The upper end of

this stem normally engages the flat underface 26 of rod 24.

Depending from plunger 21 is a stem 33 that extends through a bushing 34 that is seated in the 5 lower end of housing 30 and arranged on said stem 33 between the upper end of said bushing and the underside of plunger 31 is an expansive coil spring 35.

Arranged on the underside of spring beam 16 10 is a cover or box 36 within which is located a switch 37, to which latter is connected the conductors forming the circuit between the source of electric current supply and the motor that operates the crushing machine and projecting upwardly from said switch and disposed directly below the lower end of the stem 33, is a switch arm 15 or plunger 38.

Under normal operating conditions, rod 24 is adjusted in the distance rod so that the upper 20 end of stem 32 that forms a part of the switch actuating plunger, bears against the flat underface 26 on said rod and as long as the crusher performs its intended functions, the flat underface 25 end of the stem 32 as the yielding jaw vibrates within its normal limits.

Should an uncrushable piece of material or a 30 piece of metal such as a dipper tooth pass from the hopper 11 into the space between the jaws, the yielding jaw 14 will be moved abnormally outward against the resistance offered by the spring cushion and such movement effects a depression of the plunger 31 as the upper end of stem 32 rides downwardly on the inclined face 29 and into 35 the flat face 28, such action occurring as the result of the abnormal outward sliding movement of rod 24 and which latter is carried by the distance rod 22.

As a result of the depression of the plunger, the 40 lower end of stem 33 engages switch arm or plunger 38 and forces the same downwardly to open switch 37, thereby cutting off the current supply to the motor that operates the crusher with the result, that the latter ceases to function and consequently avoids breakage and distortion of parts due to the presence of the uncrushable object between the jaws.

After the uncrushable object has been removed from the jaws, the switch 37 automatically returns to its closed position under the influence 50 of a spring associated with arm or plunger 38 and the spring 35 actuates the plunger as the lower portion of the yielding jaw moves inward so as to reposition the flat face 26 directly above the upper end of stem 32.

The position of rod 24 having the flat underface 26 may be readily adjusted so as to regulate and control the switch throwing operation by screwing said rod into or out of the distance rod 60 22 and which adjustment is effected by engaging the slotted end of the rod 24 with a screw driver or the like.

Thus it will be seen that I have provided a relatively simple, practical, inexpensive and efficient 65 device that is wholly automatic in action and which provides a safety factor, in that the electric current supply to the motor that operates the crushing machine is cut off, in the event of

abnormal conditions arising from the entrance of an uncrushable piece of material or a foreign object such as a piece of metal, into the space between the jaws of the crusher.

It will be understood that minor changes in the size, form and construction of the various parts of my improved automatic control for crushing machines may be made and substituted for those herein shown and described without departing from the spirit of my invention, the scope of which is set forth in the appended claims.

I claim as my invention:

1. The combination with an electric motor operated crushing machine and its yielding jaw, of a spring cushion connected to the lower portion of the yielding jaw for yieldingly resisting movement of said jaw away from the swinging jaw, a fixed beam that is engaged by the rear portion of said spring cushion, a switch carried by said beam and located in the electric circuit to the motor that operates the machine, an adjustable rod arranged in the spring cushion and a spring held plunger arranged for operation in said beam and adapted to be actuated by said rod for operating said switch.

2. In an electric motor operated crushing machine having a yielding jaw, a fixed beam, an electric switch mounted on said beam, which switch is located in the electric circuit to the motor that operates the machine and a spring cushion arranged between the yielding jaw and the fixed beam, a rod connected to said spring cushion for longitudinal movement therewith, a portion of which rod extends into the fixed beam and a plunger arranged for sliding movement in said fixed beam, which plunger is adapted to be engaged by said rod and moved so as to actuate said electric switch as a result of abnormal outward movement of the yielding jaw and spring cushion.

3. In an electric motor operated crushing machine having a yielding jaw, a fixed beam, an electric switch mounted on said beam, which switch is located in the electric circuit to the motor that operates the machine and a spring cushion arranged between the yielding jaw and the fixed beam, an extensible rod pivotally connected to said spring cushion for longitudinal movement therewith, a portion of which rod extends into the fixed beam and a plunger arranged for sliding movement in said fixed beam, which plunger is adapted to be engaged by said rod and moved so as to actuate said electric switch as a result of abnormal outward movement of the yielding jaw and spring cushion.

4. The combination with an electric motor driven crushing machine having a spring cushion resisted yielding jaw and a switch located in the circuit in which the driving motor of the crushing machine is located, of a spring held plunger for actuating said switch and a member connected to the spring cushion of the yielding jaw of the machine and movable therewith for actuating said plunger and opening said switch in the event of abnormal movement of the yielding jaw.

WILLIAM W. GUEST.
